UNITED STATES PATENT OFFICE.

JOSEF GRÜNBERG, OF BERLIN, GERMANY.

SALIVA EJECTOR.

Application filed October 12, 1921. Serial No. 507,359.

To all whom it may concern:

Be it known that I, JOSEF GRÜNBERG, a citizen of the German Republic, residing at Berlin, Germany, have invented new and useful Improvements in Saliva Ejectors, of which the following is a specification.

My present invention relates to saliva ejectors for use in dental and the like operations, and has for its object to provide cer-

tain improvements whereby the ejector may be readily and effectively maintained in a sanitary condition. A further advantage of these improvements is the possibility to adjust the saliva ejector and its action to 10 the various requirements as determined by the character of the operative or the like treatment, the region of said treatment, the mouth cavity of the patient, and the degree of the secretion of the saliva. According to my present invention I am making the curved portion of the suction tube of a metal which ordinarily is sufficiently inflexible to enable said curved portion to 15 maintain its suspended position within the lower cavity of the mouth, and which at the same time is pliable to such a degree as to enable the operator to alter the curvature in conformity to both the various sizes of mouth cavities and the region out of which 20 the saliva is to be removed. Moreover, the said pliability enables the operator to readily and effectively clean the interior of the curved portion of the suction tube by previously straightening said curved portion 25 and restoring the curvature after the cleaning operation. My present invention includes also a novel structure of the nozzle into which the curved portion of the suction tube terminates and whereby said nozzle may be adjusted with regard to its drawing effect upon the saliva, while the nozzle may be entirely detached from said curved tube when the latter as well as the nozzle is to be cleaned.

I will now describe my invention with reference to the drawing in which I have shown an embodiment of the invention by way of example, the drawing forming a part of my present application.

Since the principle and working of saliva ejectors are well known in the art to which my present invention appertains, I have

only shown the curved portion of the suction tube and the improved nozzle into which said curved portion terminates.

Fig. 1 shows the curved tube in elevation with a section through the nozzle. Fig. 2 shows the detachable and adjustable part of the nozzle in elevation on an enlarged scale. Fig. 3 is a section along the line 3-3 in Fig. 2.

I make the curved portion *a'* of the suction tube *a* of a metal, like tin, which is ordinarily inflexible but pliable when force is applied in bending or straightening the same. Thus, the curvature may be altered to suit various requirements and may be removed when the tube is to be cleaned by means of an effective cleaning appliance such as a brush or the like.

The curved portion *a'* of the suction tube *a* terminates in a fixedly secured socket *b* which is internally provided with a screw thread to receive the externally screw threaded nozzle. This nozzle consists of a foot portion *c* which is preferably curved spherically on its exterior surface while a tube-like structure *c'* projects from its inner surface. This tube-like structure *c'* is provided with longitudinally extending slits *d* and carries on its cylindrical surface a screw thread fitting the aforementioned screw thread within the socket *b*.

These slits *d* may be arranged in diametrical opposition which arrangement simplifies the cleaning operation since with such an arrangement a mechanical cleaning appliance may be passed crosswise through each pair of opposed slits *d*.

The spherically curved foot portion of the nozzle is of such a thickness that a drawing off of the saliva film or skin is prevented while only the saliva excess is subjected to the drawing effect of the slits *d* through which the suction of the tube *a*, *a'* acts upon any fluid within the vicinity of the nozzle.

The effective sectional area of said slits *d* can be adjusted by screwing said nozzle *c* more or less into the socket *b*.

When the saliva ejector and its parts are to be cleaned, the nozzle *c* is entirely detached from the suction tube *a*, *a'* and subjected to a cleaning treatment. For the same purpose the tube portion *a* is then

straightened whereupon a brush can be passed through the tube interior. After the cleaning treatment the nozzle is restored and the tube a' rebent to its curved form.

5 What I claim as my invention and desire to secure by Letters Patent of the United States, is:—

1. In a saliva ejector, a curved tube of a metal that is ordinarily inflexible, and pliable when subjected to a plying force, and 10 a nozzle-like curved tube termination, comprising, in combination, a detachable hollow plug, a thickened end portion, longitudinally extending drawing-off slits in said

hollow plug, and means for adjusting the active length of said drawing-off slits.

2. In a saliva ejector, a curved tube of a metal that is ordinarily inflexible and pliable when subjected to a plying force, an internal screw thread at the end of said 20 curved tube, a plug adapted to be screwed into said screw threaded tube end and comprising a solid head, a hollow stem, and longitudinally extending slits in said hollow stem, said slits being disposed in diametrical 25 opposition.

JOSEF GRÜNBERG.
